UNITED STATES PATENT OFFICE

EDWARD C. KLINE, OF STREATOR, ILLINOIS

BOILER

Application filed March 11, 1929. Serial No. 346,136.

My invention relates to heat exchange devices of the class known as boilers and has to do more particularly with devices primarily designed for imparting heat to a fluid 5 which is to be utilized in the heating of a dwelling place or other building.

It has long been recognized as desirable in boilers of the type referred to that the fluid be conducted in thin streams, films or 10 columns in order that the maximum number of molecules of the fluid may be brought into contact with the surface of the heating members. However, in order to attain a high efficiency by this method, it has not been possible to provide circulation of a sufficient 15 quantity of water to meet the average heat requirements of a dwelling of ordinary size and still maintain the size of the boiler within practical limits.

20 A particular object of my invention, therefore, is to provide a boiler of high thermal efficiency which at the same time will have a high capacity; that is to say, which will be capable of transferring a large number of 25 heat units to a large quantity of heating fluid per unit of time.

Another object is to provide such a device which will occupy a minimum of space.

30 A further object is to provide an improved method of heat exchange.

Still another object is to provide such a device which will be simple in construction, inexpensive to manufacture and durable.

35 Various other objects and advantages of the construction herein shown and described will be obvious to those skilled in the art from the disclosure herein given.

To this end my invention consists in the 40 novel construction, arrangement and combination of parts herein shown and described, and more particularly pointed out in the claims.

45 Referring now to the drawings, forming a part of this specification and representing a preferred embodiment of the invention;

Fig. 1 is a sectional view taken on a vertical plane through a boiler embodying my invention;

Fig. 2 is a sectional view taken substantially on the line 2—2 of Fig. 1; and

Fig. 3 is a sectional view taken substantially on the line 3—3 of Fig. 2.

The numeral 10 in Fig. 1 represents a radiator of any suitable type adapted to utilize a heat exchange fluid such as hot water, steam or the like, and forming part of the heating system of a building. The radiator 10 communicates by means of a conduit 12 with a boiler indicated generally at 13 embodying my invention.

The boiler 13 comprises a setting 14 of brick or other suitable material. The conduit 12 communicates, by means of a pipe 15 extending through a wall of the boiler setting 14, with a return header 17. Connected to the header 17 are a plurality of nipples 18 and 18'. It will be noted that the nipples 18 and 18' extend in rows spaced substantially ninety degrees apart. These nipples are connected by means of elbows 19 or the like to tubes 20 and 20' which are arranged in parallel rows vertically spaced from each other. As shown in Fig. 2, however, the individual tubes of each row are staggered with reference to the tubes of the other row in order to facilitate complete circulation of the gases of combustion, so that the tubes of the upper row may not be shielded by the lower tubes. The tubes 20 and 20' are connected by means of elbows 21 to nipples 22 and 22' arranged in parallel rows and providing communication with a water baffle 25.

The water baffle 25 comprises bottom and top plates 26 and 27 respectively which are spaced a relatively short distance apart in parallel relation and connected by means of integral side walls 28 so as to be substantially in the form of a rectangular parallelopiped. The baffle 25 is substantially flush with the inner walls of the boiler setting 14 on three

sides thereof and is secured to the setting by means of lugs 30 which are preferably formed integrally with the baffles.

At the free end of the baffle are nipples 31 and 31' arranged in parallel rows in the upper plate 27 which provide fluid outlets from the baffle. These nipples communicate by means of elbows 33 with rows of tubing 34 and 34'. These tubes are arranged in parallel rows and in staggered relation to each other in substantially the same manner as the tubes 20 and 20'.

The tubes 34 and 34' communicate with a water baffle 38 which is substantially similar to the baffle 25. Furthermore, the baffle 38 is staggered with reference to the baffle 25; that is to say, it is spaced away from the opposite wall to that from which the baffle 25 is spaced in order that the gases of combustion may be forced to circulate in a circuitous path around the tubes and baffles.

Baffle 38 communicates by means of nipples and elbows similar to those described above, with tubes 42 and 42' which are arranged similarly to the tubes 20 and 20'. These tubes 42 and 42' communicate by means of elbows and nipples with a water baffle 45 which is substantially similar to the baffles 25 and 38, and is staggered with reference to the baffle 38. The baffle 45 is preferably substantially flush with the top wall of the boiler setting 14.

The baffle 45 communicates by means of an outlet tube 47 with the radiators of the heating system, including the radiator 10. A flue 50 may be provided at any suitable point in the upper part of the boiler setting and suitable manholes (not shown) for facilitating the cleaning of the baffles, tubes, etc. may be disposed at desired points in the setting.

The water baffles may very conveniently be formed by casting or by welding or otherwise, the lugs 30 being preferably formed as integral parts thereof, and it is thus apparent that these members may be made very economically. Inasmuch as the other parts, such as the tubes, elbows, nipples, etc. are standard articles, it is obvious that boilers embodying my invention may be constructed very inexpensively.

While the boiler may be used in either a steam or hot water heating plant and may, in fact, be used for the production of steam for industrial use, I have had in mind the application of my invention particularly to hot water heating systems. In such a case, the system is filled with water from a suitable source (not shown), and a source of heat (not shown) is provided in the lower part of the boiler setting. Such a source of heat may be produced from coal, oil or other suitable fuel and with any convenient type of grate or burner. As the gases of combustion arise, they will be forced to circulate in a tortuous

path through the tubes and along the surfaces of the water baffles. Such a tortuous path is insured by the staggered relation of the baffles, and the staggered relation of the rows of tubing assures that the hot gases will make efficient contact with every tube, inasmuch as no tube is shielded.

In one embodiment the baffles are about eight feet long and two feet wide, the plates being spaced about an inch apart. It will thus be seen that, with these baffles, the hot gases will be forced to travel over 24 feet before reaching the flue all the while maintaining contact with the surfaces of the heat exchange members. Furthermore, in the embodiment mentioned the boiler may be constructed with a surprisingly low weight, in view of its high heating area.

By providing a plurality of rows of tubing to conduct fluid to and from each of the water baffles, the capacity of the boiler is greatly increased.

The capacity of the tubing between each pair of baffles is preferably greater by, say, 25 percent than that of the heating system outside of the boiler, in order to facilitate circulation. While I have shown two rows of tubing as serving each baffle, it is obvious that any convenient number of rows might be utilized, and I am therefore not to be limited to the specific number or arrangement shown, except as specified in the appended claims. It is also to be noted that each molecule of water in the heating system is forced to travel the entire length of all of the baffles, and is also forced to travel the entire length of the tubing between each of the baffles. Inasmuch as the baffles are relatively thin and the tubing is of relatively small diameter, preferably one inch, it is obvious that practically all of the water in the system is brought into contact with an extremely large area of heating surface in spite of the fact that boilers embodying my invention may be set up in comparatively small space. Thus in the embodiment referred to the total travel of each molecule within the heating elements is about 48 feet. Furthermore, such an embodiment may be set up in a total height of about four feet. This means not only economy of space but also improved circulation in increasing the drop from the radiators to the boiler.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned. Thus, while I have shown three baffles, it is obvious that this number may be varied in either direction to meet various requirements.

What I claim as new and desire to secure by Letters Patent is:

1. In a boiler of the class described, a setting, a plurality of relatively thin hollow baffles arranged in said setting so as to cause the gases of combustion to follow a circuitous path, and tubular means forming the sole outlet of each of said baffles and serving to conduct fluid therefrom to the adjacent baffle thereabove, said tubular means being so arranged that a given quantity of heating fluid will be caused to circulate throughout substantially the entire length of each of said baffles in the same direction.
2. In a fluid heating system, a boiler setting, a plurality of relatively thin hollow baffles in said setting, and tubular means forming the sole outlet of each of said baffles and serving to conduct fluid therefrom to the adjacent baffle thereabove, said tubular means having a fluid capacity at least equal to that of any other part of said system.
3. In a fluid heating system, a boiler setting, a plurality of relatively thin hollow baffles arranged in staggered relation in said setting, and tubular means forming the sole outlet of each of said baffles and serving to conduct fluid therefrom to the adjacent baffle thereabove, said tubular means having a fluid capacity at least equal to that of any other part of said system.
4. In a boiler of the class described, a setting, a plurality of relatively thin hollow baffles arranged in staggered relation in said setting, and a plurality of tubes connected to said baffles and extending longitudinally thereof for conducting fluid from one baffle to an adjacent baffle thereabove, whereby a given quantity of heating fluid is caused to circulate throughout substantially the entire length of each of said baffles.
5. In a boiler of the class described, a setting, a plurality of relatively thin hollow baffles arranged in said setting so as to cause the gases of combustion to follow a circuitous path, and a plurality of tubes connected to said baffles and extending substantially parallel thereto and in staggered relation with respect to each other whereby a given quantity of heating fluid is caused to circulate throughout substantially the entire length of each of said baffles.
6. In a boiler of the class described, a setting, a plurality of relatively thin hollow baffles arranged in said setting so as to cause the gases of combustion to follow a circuitous path, and tubular means forming the sole outlet of each of said baffles and serving to conduct fluid from adjacent the end of one baffle to the remote end of an adjacent baffle thereabove, said tubular means being so arranged that a given quantity of heating fluid will be caused to circulate throughout substantially the entire length of each of said baffles.
7. In a boiler of the class described, a set-

ting, a plurality of relatively thin hollow baffles arranged in staggered relation and having their free ends spaced from opposite walls of the setting, and a plurality of tubes connected to said baffles and extending longitudinally of the baffles for conducting fluid from the free end of one baffle spaced from one of said walls to the free end of an adjacent baffle spaced from the other of said walls whereby a given quantity of heating fluid is caused to circulate throughout substantially the entire length of each of said baffles in the same direction.

In witness whereof, I hereunto subscribe my name this 22nd day of February, A. D. 1929.

EDWARD C. KLINE.
